UNITED STATES PATENT OFFICE.

JOSEPH FLANNERY, OF PHILADELPHIA, PENNSYLVANIA.

FURNACE.

SPECIFICATION forming part of Letters Patent No. 251,856, dated January 3, 1882.

Application filed April 19, 1881. (No model.)

To all whom it may concern:

Be it known that I, JOSEPH FLANNERY, of Philadelphia, in the county of Philadelphia and State of Pennsylvania, have invented certain new and useful Improvements in Furnaces; and I do hereby declare the following to be a full, clear, and exact description of the invention, such as will enable others skilled in the art to which it pertains to make and use it, reference being had to the accompanying drawings, which form part of this specification.

My invention relates to an improvement in furnaces; and it consists, first, in building a fire at or near the rear end of the boiler, in addition to the fire which is lighted under its front end, and forcing the whole of the products of combustion up through this second fire at the rear end of the boiler, and providing it with suitable flues for the admission of air.

The object of this part of my invention is to arrest the soot from the products of combustion from the fire under the front end of the boiler, and to convert the carbonic-acid gas into a carbonic oxide, and to decompose the vapors of water into its gases, whereby the neutral gases are converted into combustible or heating gases and a very intense heat produced, as well as to make the furnace a smoke-consumer.

The second part of my invention consists in placing a bed of limestone (carbonate of lime) back of the fire, which is lighted under the front end of a boiler, and which is to be used in connection with a secondary fire, which is made at the rear end of a boiler. The object of this part of my invention is to disengage large volumes of carbonic-acid gas contained in the carbonate of lime (limestone) by means of the heat in the products of combustion, and this carbonic-acid gas, passing through the incandescent bed of coals at the rear end of the furnace, takes up a certain quantity of carbon, and is thereby converted into carbonic oxide, and thus a valuable combustible gas is furnished in large quantities at a trifling cost.

The third part of my invention consists in the use of a curved arch over the top of the secondary fire, for the purpose of deflecting the heating-gas directly into the rear ends of the

flues. The object of this part of my invention is to deflect the heated gas directly into the flues of the boiler, so that as little heat as possible will be absorbed by the surrounding settings, and thus the heat is applied more directly to heating the boiler and generating steam than it would be where any other form of setting was used.

Figure 1 is a front elevation of a furnace embodying my invention. Fig. 2 is a longitudinal vertical section of the same. Fig. 3 is a vertical cross-section taken on the line 1 2 of Fig. 2. Fig. 4 is a horizontal longitudinal section taken through the furnace, so as to show all three sets of grate-bars. Fig. 5 is a vertical cross-section on the line 3 4 of Fig. 2.

A represents the outside wall of my furnace-setting, made of common brick or any other suitable material; and B, the inside wall, of refractory material of any kind, and in between the two walls is formed an air-chamber, into which air is taken at the top or any other suitable point and heated by the radiated heat that is imparted to the inner wall, and then this heated air is fed to the fires through suitable passages prepared for this purpose.

Under the front end of the boiler is the usual furnace, D, into which the fuel is fed through an inclined passage-way, E, which is made long enough to extend across the front of the furnace, and in which the coal is heated to such an extent as to liberate a large quantity of the gas contained therein before the coal is fed upon the grate. When it is desired to feed this coal forward upon the grate it can be readily done by using any suitable tool through the opening F just below this inclined passage-way. By thus coking the fuel before it is fed forward upon the grate a large proportion of gas is given off and consumed under the furnace of the boiler. This gas being liberated in the manner described and consumed under the front end of the boiler prevents the usual large amount of carbou or soot being given off in a solid form, and thus assists to make the furnace a smoke-consumer.

Just back of the projecting wall is placed a second set of grate-bars, Y, and upon these grate-bars is placed a suitable quantity of carbonate of lime in the form of oyster-shells or

limestone, and the heat of the products of combustion passing through this carbonate of lime liberates large quantities of carbonic-acid gas. This carbonate of lime also serves to prevent 5 any soot or other solid matter from passing in with the products of combustion, and thus assists in making the furnace a smoke-consumer. As fast as the carbonate of lime parts with its carbonic-acid gas it settles down upon the grate-bars, and it can be removed through a suitable door made through the side of the setting for this purpose, and then renewed whenever it is necessary.

As here shown, just back of the bed of carbonate of lime a water-leg is formed upon the rear end of the boiler, and through this water-leg is made a flue, H, through which the products of combustion pass. This water-leg, however, is not necessary, and in applying my invention to boilers which have no water-leg any other flue or construction that may be desired will be used.

At the rear end of the flue is formed a reservoir, I, in which a suitable quantity of water is kept, and which water is converted into steam by the heated products of combustion coming in contact therewith. Above this reservoir is placed a set of grate-bars, X, which are formed from tubes which are connected with the lower 25 and upper parts of the boiler, so as to keep a constant circulation through them. These grate-bars being thus made and kept filled with water serves a double purpose—that of preventing the bars from being so rapidly consumed or destroyed by heat and assisting in the generation of steam. Upon these grate-bars is placed a suitable quantity of carbon, in the form of either coal or coke, and through this body of carbon the whole products of combustion, together with the vapor of water, are made to pass. The heat from the products of combustion converts this carbon into an incandescent bed of coals, and the carbonic-acid gas, passing up through this incandescent fire, absorbs a certain quantity of carbon, and is converted into carbonic oxide, and thus a neutral gas is converted into a combustible one. The vapor of the water passing up through this incandescent fire is resolved into its elements of 35 hydrogen and oxygen, and the hydrogen, mingling with a quantity of atmospheric air which passes in through the flue K, is consumed, and the oxygen and the vapor combine with the carbon of the fire, and are also consumed. Just 40 below the grate-bars is made a second flue, L, through which a suitable quantity of heated atmospheric air is permitted to pass when needed for the purpose of aiding the combustion of the carbon. By means of this secondary 45 incandescent fire, which is ignited by the products of combustion from the fire under the front end of the furnace, all of the solid products of combustion, such as soot and ashes, are prevented from passing up and being deposited in the flues, whereby a very great saving of time and trouble is effected in the oper-

ation of the boiler. As both the soot and ash deposited in the flues act as non-conductors, and thus prevent the ready absorption of heat, it will readily be seen that by keeping the 70 flues clean a large portion of heat which would otherwise be lost is made available, and all the loss of time and trouble necessary to keep the flues clean is entirely done away with. Where this secondary fire is used, and the products of 75 combustion made to pass up through it, all of the carbonic-acid gas and all of the unconsumed carbon in the shape of soot are allowed to pass away through the stack and are lost, whereas where this incandescent fire is used nearly the 80 whole of the soot and the carbonic-acid gas is utilized in the production of steam.

Where this invention is to be applied to furnaces already in use, and where there is not sufficient room for the secondary fire at the 85 rear end of the boiler, the fire may be formed at one end of the setting, and the products of combustion will then be made to pass along the full length of the boiler, and then down through a flue and pass up through this 90 incandescent fire, and then back into the flue through which it is intended that it shall pass. It is not necessary that this fire should be made in the location here shown, as any other location will answer equally as well, though the 95 manner here shown is preferred. Above the top of the chamber formed for this incandescent fire there is placed a curved arch, N, which is so shaped as to deflect the heated gas upward directly into the rear ends of the flues O, 100 which extend horizontally through the boiler. By this form of arch but very little heat is absorbed, and by deflecting the heated gases directly into the tubes and against the end of the boiler a great saving in heat is effected. 105 After the gases have passed through the flues O they rise upward at the front end of the boiler and pass off into the stack, which may be located at any convenient point. Should a battery of boilers be used, a bed of carbon 110 similar to what is here shown will be placed under each boiler, at any suitable point, so that the products of combustion will be utilized, as above described.

Although my invention is here shown as 115 applied to the furnace of a boiler, it is obvious that it can be used in connection with furnaces of different kinds, where it will accomplish the same results in forming a smokeless furnace, and to utilize the unconsumed gases which 120 pass off in the products of combustion and are lost.

I am aware that a secondary fire has been placed in the rear end of the fire which is made under the front end of the boiler; but in this 125 case the products of combustion pass over the top of the secondary fire, and in no case pass up directly through it, as here shown, and hence I do not claim a secondary fire *per se*.

Having thus described my invention, I 130 claim—

1. In a furnace, the combination of a fire

which is made in the front end of the furnace with a bed of carbon through which the whole products of combustion of the fire in the front of the furnace pass, and a suitable flue, K L, for admission of air to the secondary fire, substantially as shown.

2. In a furnace, the combination of the fire made in the front end of the furnace, a bed of carbonate of lime through which the products 10 of combustion pass, a suitable air-flue, K L, for the admission of air to support combustion, and a bed of carbon which forms an incandescent fire, and through which also the products of combustion and the gas disengaged from the carbonate of lime pass, substantially as described.

3. In a furnace, the combination of a fire in the front of the furnace, a vaporizing-pan, a

suitable flue for the admission of air to the secondary fire, and a secondary fire-chamber, substantially as set forth.

4. In a furnace, the process described of liberating carbonic-acid gas by passing the products of combustion through a bed of carbonate of lime, and then passing the gas thus liberated through a secondary fire, where it is made to mingle with atmospheric air above and below the grate, and thus converted into a combustible gas, substantially as specified.

In testimony whereof I affix my signature in presence of two witnesses.

JOSEPH FLANNERY.
